US00D330541S

United States Patent [19]

Burrow et al.

[11] Patent Number: Des. 330,541

[45] Date of Patent: ** Oct. 27, 1992

[54] MAGNETIC CORE

[75] Inventors: **Marcus D. Burrow**, Garland; **James D. Burts, Jr.**, McKinney; **Kevin D. Jackson**, Garland; **Paul A. Jeffries**, Plano; **Clayton L. Sturgeon**, Richardson, all of Tex.

[73] Assignee: **Powercube Corporation**, Billerica, Mass.

[**] Term: **14 Years**

[21] Appl. No.: **569,452**

[22] Filed: **Aug. 17, 1990**

[52] U.S. Cl. **D13/183; D13/118**

[58] Field of Search **D13/183; 336/65, 67, 336/192; 210/222, 223**

[57] CLAIM

The ornamental design for magnetic core, as shown and described.

DESCRIPTION

FIG. 1 is a perspective view of a magnetic core showing our new design;

FIG. 2 is a top plan view thereof;

FIG. 3 is a bottom plan view thereof;

FIG. 4 is a front elevational view thereof, the rear being identical;

FIG. 5 is a side elevational view thereof the opposite side being identical; and,

FIG. 6 is a cross-sectional view thereof taken generally along sectional lines 6—6 of FIG. 4.

FIG. 1

FIG. 2

FIG. 3

FIG. 4

FIG. 5

FIG. 6
